UNITED STATES PATENT OFFICE.

AUGUST C. HUMMEL, OF MILFORD, OHIO.

PNEUMATIC CLEANER.

1,184,959.

Specification of Letters Patent. Patented May 30, 1916.

Application filed October 7, 1915. Serial No. 54,639.

To all whom it may concern:

Be it known that I, AUGUST C. HUMMEL, a citizen of the United States, residing at Milford, in the county of Clermont and State of Ohio, have invented certain new and useful Improvements in Pneumatic Cleaners, of which the following is a specification.

My invention relates to pneumatic cleaners and sweepers; and its object is to combine with the brushing action of a carpet sweeper a pneumatic cleaning action.

A further object of my invention is to simplify and increase the efficiency of a pneumatic cleaner.

My invention consists in the combination of parts and in the details of construction and arrangement of parts as will herein be more fully described and claimed.

In the drawings: Figure 1 is a bottom plan view of a device embodying my invention, a part being shown as broken away; Fig. 2 is a vertical longitudinal section on a plane corresponding to the line 2—2 of Fig. 1, but the position of the nearer bellows being indicated by dotted lines; and Fig. 3 is a vertical cross section on a plane corresponding to the line 3—3 of Fig. 2, a part being shown as broken away; and Fig. 4 is a sectional detail, on a plane corresponding to the line 4—4 of Fig. 2, showing the arrangement of the filling pieces and gaskets at the rear of the dust chamber.

As I prefer to construct my invention, there is a casing made up of sides 1 joined at the front by thin vertical boards 2 and 3 below, and thin rearwardly slanting boards 4 and 5, attached to the upper edges of the boards 2 and 3, respectively, the boards 3 and 5 being spaced back from the boards 2 and 4, forming the nozzle 6.

Immediately under the part 5 is a strip 7, and spaced back from this a considerable distance, at the top of the casing and somewhat therebelow, respectively, are strips 8 and 9. All of these strips 7, 8 and 9 run from one side 1 to the other, and the lower strip 9 has its lower side extending some distance below the lower side of the forward strip 7, forming one abutment for a drop door 10 which has its front upper side beveled to fit the horizontal lower side of the strip 7. Adjacent to the sides 1 there are abutment pieces 11 of shape to fit the spaces on the inner surfaces of the sides 1 defined by the inner end of the nozzle 6 and the inner sides

of the strip 7, drop door 10, strip 9 and strip 8, and also coming flush with the upper edge of the side 1; and around the lower edges of these pieces 11 and the strips 7 and 9 is a suitable gasket material 12, such as leather, which the door 10 closes against.

Filling pieces 13, against the sides 1, and a filling piece 14 at the middle, are fitted between the lower edge of the upper strip 8 and the upper edge of the lower strip 9, so that two passages are defined back to the rear section of the casing. The front upper side of the strip 9 slants at an angle to the front sides of the upper strip 8 and these filling pieces 13 and 14, and upon the pieces 11, triangular filling pieces 15 fit back against the strips 8 and 9 and the filling pieces 13, with their front edges straight from the upper edge of the strip 8 to the lower edge of the strip 9. From said edge of the strip 8 to said edge of the strip 9, and from the front edge of one piece 15 to the other, is stretched a sheet 16 of dust-arresting foraminous material, (shown as broken away in Fig. 3). The casing has a top 17 fixed to the upper edges of the sides 1 and the upper nozzle-forming piece 4. Thus a dust chamber 18 is inclosed, with which the atmosphere has communication through the nozzle 6 at the top of its front side: and which communicates with the rear of the casing through the passages behind the foraminous sheet 16; and which has its bottom formed by the strip 9 and drop door 10, the upper sides of which slant abruptly downward to their meeting line at the lower edge of the foraminous sheet 16.

Rearwardly, the upper strip 8 and lower strip 9 are rabbeted on their lower and upper sides, respectively, and there are filling pieces 19 and 20 at the sides and in the middle, respectively, so that two distinct sockets are formed for the front ends of the two sets of bellows 21. Each set of bellows is made up of a top and bottom 22 and 23, respectively, a middle diaphragm 24 and flexible sides 25 fixed to the edges of the top and bottom 23 and diaphragm 24 on the sides and at the rear. The top and bottom 22 and 23 are fixed to the upper and lower edges, respectively, of upper and lower strips 26 and 27 which have horizontal rows of holes 28 and 29, respectively, and having interposed between them a flexible hinge piece 30, preferably of leather, extending

rearwardly therefrom into a rather deep groove along the horizontal front edge of the diaphragm 24. The bellows top 22 is substantially parallel with the casing top 17, 5 and at the rear and substantially midway of the length of the bellows there are spacing pieces 31 and 32 against the lower sides of which the bellows top 22 fits. The bellows bottom 23 slopes downward rearwardly, and about midway of the length of the bellows is the sweeper casing back 33 extending upright from one end to the other with the sweeper casing top 34 extending from the top of this back 33 up to the upper 10 side of the rabbet in the lower strip 9. On the rear sides of the strips 8 and 9 and pieces 13 and 14, around the passage between them, there are gaskets 35, preferably of leather, so that communication is afforded from the 15 dust-chamber to the interior of the bellows above and below the diaphragm 24 through the holes 28 and 29; the bellows being supported in such a connecting position by resting on the sweeper casing top 34. The bellows is held in this position by a back 36 which is screwed to the back ends of the casing sides 1, preferably having rabbeted joints therewith; and which has on its front side upper and lower cleats 37 and 38 that 20 hold the bellows top 22 up and the bellows bottom 23 down, respectively. Also, preferably there is a lowermost cleat 39 on the front side of the back 36 fitting up against the lower rear edge of the bellows bottom 23. These bellows 21 are made of such 25 width relative to the casing that considerable spaces are left at opposite sides, in which spaces are located the bellows driving wheels 40 which are fixed on the ends of a crank shaft 41 which has cranks 42 between the wheels 40 and the respective bellows, and suitably held in radial slots 43 in the inner sides of the wheels 40, so that the crank shaft 21 will turn with the wheels. 30 The ends of the crank shaft extend past the wheels into bearing blocks 44 fastened on the interiors of the casing sides 1 near their bottoms between the sweeper casing back 33 and the back 36. Also there are bearings 35 45 for the crank shaft 41 on the lower sides of the bellows bottoms 23. A bottom 46 is preferably provided below the bellows, (shown as broken away in Fig. 1.) Pitmen 47 connect the cranks 42 with the brackets 48 on the sides of the bellows diaphragms 24. The cranks are extended at right angles to each other; thus giving four impulses at each revolution. Inlet valve flaps 49 are provided over the rear ends of the holes 28 and 29, and outlet valves 50 are provided in the tops and bottoms 22 and 23 of the bellows. 55

The nozzle 6 comprises a slotted strip of molding 51 along the bottoms of the pieces 2 and 3, which molding is covered by a suit

able smooth metallic facing piece 52 which bears on the surface to be cleaned.

Immediately to the rear of the nozzle 6 is the sweeper casing front 53 running from one side 1 to the other. The lower edges 70 of the back 33 and front 53 of the sweeper casing are rabbeted on the sides toward each other, and pans 54 are swung on pivots 55 up against the rabbeted parts, there being a space between the pans in which is located 75 the brush 56 extending out through slots 57 in the sides 1 with driving pulleys 58. Mounted on the outer sides of the sides 1 are horizontal arch bars 59 which carry, at their middles, levers 60, each comprising a 80 vertical and a rearwardly extending part having pivots 61 in the arch bars 59 and in their rearwardly extending parts, and having studs 62 projecting inwardly near the intersections of their parts; these studs 62 85 forming the bearings for the brush 56 by being received in holes in the ends of the brush.

The sweeper driving wheels 63 are mounted inside the arch bars 59 at the front and 90 rear of the brush pulleys 58 on spindles 64 that extend from one side of the apparatus to the other through openings 65 in the sides 1, and are fixed in short links 66 running forwardly and rearwardly from the front 95 and rear spindles 64, respectively, and pivoted on screws 67 running into the sides 1 of the casing. The wheels 63 are held on their spindles 64 by bearing against the inner sides of the arch bars 59. The holes 65 in 100 the casing sides 1 are of diameter greater than that of the spindles 64; so that the wheels 63 may work up and down, swinging on the links 66. Endless flexible belts 68 pass around pulleys 69 on the inner sides 105 of the wheels 63, and the upper stretches of the belts 68 pass under the brush pulleys 58. This arrangement of the belt holds the wheels 63 down against the weight of the apparatus, and the articulated mounting of 110 the wheels 63 enables them to always bear on the surface being cleaned, whatever the relative positions of the bellows driving wheels 40 at the rear and the nozzle facing piece 52 at the front. Also, it causes the 115 wheels 63 to bear part of the weight of the forward part of the cleaner, minimizing the pressure of the nozzle on the surface being cleaned, and thus decreasing the friction and wear. 120

From the foregoing it will be understood that the sweeper brush 56 is designed to sweep up the heavier particles and dust, and the bellows acting through the nozzle 6 are designed to draw the dust thus raised up into the dust chamber 18. It will also be seen that if the drop door 10 of the dust chamber is dropped, the dust from the dust chamber will be discharged into the forward 125 pan 54 of the sweeper. This, together with 130

the novel downwardly slanting bottom of the dust chamber, constitutes a marked improvement in the apparatus without decreasing its effectiveness as a vacuum cleaner.

- 5 For manipulating the drop door 10 it is swung on coil springs 70 each with a downward arm 71 fixed in the rear of the sweeper casing front 53 and a rearward arm 72 fixed in the lower side of the drop door 10; and 10 handles 73 lying outside the casing at opposite sides with shanks 74 extending through bearings 75 in the casing sides 1 and bent backward under and screwed to the drop door 10. Thus, pressing down on the 15 handles 73 drops the door 10 with the shanks 74 as pivots, and the springs 70 close the door 10 tightly when the handles are released. The gasket 11 insures that the dust chamber is air-tight when the drop door 10 20 is thus closed.

As before described, the brush 56 is pivoted and hung on the levers 60. When these levers are swung forward the brush is lowered and when swung backward the brush 25 is raised. To hold these levers 60 in any one of a number of adjusted positions, brackets 76 are mounted on the outer sides of the casing with laterally extending parts 77 having notched edges within the notches of which 30 the levers 60 have inward lateral extensions 78.

For dumping the sweeper pans 54, a bent spring 79 straddles the brush center and has lower ends 80 engaging in the respective 35 pans below their pivots 55; while a lever 81 is pivoted on one of the screws that hold the bracket 76 on the outside of the casing and extends inward through an opening in the casing side and through a segmental slot 82 40 in the bracket 76 and over to the loop 84 of the spring 79, where it has an ear 83 with an opening through which the loop 84 of the spring extends. Thus by bearing down 45 on the outer end of the lever 81 the spring 79 is raised, swinging the pans 54 open and drawing its members together; and when the lever 81 is released it forces the pans 50 shut, due to its resiliency. I have improved the connection of this spring with the manipulating element by forming the loop 84 therein rather than merely a single bend; so that the spring 79 is prevented from creeping one way or the other through the ear 83 of the lever 81.

55 The bail 85 has a socket 86 to receive a handle, and is pivoted in plates 87 on the sides of the casing slightly to the rear of the sweeper casing. This bail is held in upright position by spring clips 88 on the outer 60 sides of the casing a short distance above the pivot plates 87.

It will be understood that the bellows 21 are readily removable by removing the casing back 36 and disconnecting the bearings 65 45 and pitmen 46; without disturbing any

of the other parts of the apparatus. This is very convenient in case of necessity of repairs or renewal of the bellows.

Cushioning strips 89 are mounted along the sides of the arch bars 59 by having 70 their parts confined in openings close to the attachment of the arch bars to the casing sides between the edges of these openings and the casing sides (Fig. 1). Another cushioning strip 90 may pass around the 75 front of the sweeper from the front end of one arch bar to the other and be held in the same manner along with the side cushioning strips 89. My vacuum cleaner, so constructed that removal of the nozzle is unnecessary, renders practical the provision of such a cushioning strip along not only the sides but around the front of the apparatus, thereby providing additional protection against marring both of the cleaner casing 80 and of furniture or other objects which may be struck while using the apparatus.

The peculiar relation between the wheels and brush and sweeper insures constant driving action for both pneumatic and brush 90 parts of the apparatus as well as a broom action for the brush.

While the several advantages above mentioned are attained to a highly satisfactory degree, the simplicity of the structure recommends it for economical manufacture, as 95 well as for convenience, reliability and durability in use.

Having fully described my invention, what I claim as new and desire to secure by 100 Letters Patent is:

1. In a pneumatic cleaner, a nozzle, a dust chamber to the rear of and communicating with said nozzle, means for drawing dust through said nozzle into said dust chamber, sweeping means, means below said dust chamber for receiving sweepings from said sweeping means, said dust chamber comprising a drop door, and means extending outside said cleaner for dropping said door 105 to discharge dust from said dust chamber into said means that receives the sweepings.

2. In a pneumatic cleaner, a nozzle, a dust chamber to the rear of and communicating with said nozzle, means for drawing dust through said nozzle into said dust chamber, sweeping means, means below said dust chamber for receiving sweepings from said sweeping means, said dust chamber comprising a bottom made up of parts slanting 115 down toward each other, one of said parts being movable downwardly, and means extending outside said cleaner for moving said part downwardly to discharge dust from 120 said dust chamber into said means that receives the sweepings.

3. In a pneumatic cleaner, a casing with a fixed nozzle, sweeping means, a dust chamber communicating with said nozzle and above the sweeping means, a bellows to 125 130

draw dust through said nozzle into said dust chamber, lying above the sweeping means and entirely below the level of the top of the dust chamber, means for operating said bellows, a top for said cleaner extending over the dust chamber and bellows, and a top for said sweeping means slanting rearwardly, said bellows tapering forwardly and being wedged between the top of the sweeping means and the top of the cleaner, and a removable back for said cleaner holding said bellows in wedged position.

4. In a pneumatic cleaner, a dust chamber, means for drawing dust into said chamber, sweeping means, and means for receiving sweepings from the sweeping means, a drop door forming part of the bottom of said dust chamber, a coil spring yieldably holding said door up and closing the bottom of the dust chamber, and a pivot for said drop door, whereby it may be dropped and dust may be discharged from said dust chamber into said sweeping means.

5. In a pneumatic cleaner, a dust chamber, means for drawing dust into said chamber, sweeping means, and means for receiving sweepings from the sweeping means, a drop door forming part of the bottom of said dust chamber, a coil spring yieldably holding said door up and closing the bottom of the dust chamber, and a handle com-

prising a part extending outside the cleaner, a shank extending into and bearing in a part of the cleaner, and a rearward part fixed to said drop door whereby said shank 35 forms a pivot for said drop door, and whereby said door may be dropped and dust may be discharged from said dust chamber into said means for receiving sweepings by engagement with said handle.

6. In a pneumatic cleaner, a casing with a fixed nozzle, a sweeping means and means for receiving sweepings from the sweeping means, a dust chamber over said means for receiving sweepings, means to draw dust 45 through said nozzle into said dust chamber, a front for said means for receiving sweepings, to the rear of and under said nozzle a drop door forming part of the bottom of said dust chamber, a coil spring with a 50 downward member engaging with said front, and a rearward member engaging with said drop door, yieldably holding said door up and closing the bottom of the dust chamber, and a pivot for said drop door, 55 whereby it may be dropped and dust may be discharged from said dust chamber into said means for receiving sweepings.
